UNITED STATES PATENT OFFICE.

JOHN M. PALMER, OF CHICAGO, ILLINOIS.

VALVE.

1,258,937.

Specification of Letters Patent. Patented Mar. 12, 1918.

Application filed March 25, 1915. Serial No. 16,834.

To all whom it may concern:

Be it known that I, JOHN M. PALMER, a citizen of the United States, residing at Chicago, in the county of Cook and State 5 of Illinois, have invented a certain new and useful Improvement in Valves, of which the following is a full, clear, concise, and exact description, reference being had to the accompanying drawings, forming a part of 10 this specification.

My invention relates to valves for controlling fluid flow and its object is two-fold—the effectiveness of the closed position, and durability.

15 With reference to the first named object, I provide means for spreading the valve member or gate so that it will firmly engage its seat or seats to absolutely prevent the passage thereby of any of the fluid intended to be controlled. This spreading action I secure automatically by the operation 20 which closes the valve and it is a resultant of continued actuation of the valve handle after the valve has reached its closing position.

25 With reference to the other object, that of durability, my invention is concerned with the protection of the valve seat and, consistent with this object, I provide what 30 I term "a covered seat valve",—that is, I provide a valve seat which, when the valve member or gate is moved therefrom, is protected either by being entirely covered, which is the case in the preferred embodiment 35 of my invention, or by being nearly covered but so completely protected as to be guarded against the injurious action of the rushing passage of fluid through the valve chamber, such as the rush of steam, 40 for instance.

I have illustrated several forms of my invention.

Figure 1 illustrates in vertical axial cross-section the simplest form thereof.

45 Fig. 2 illustrates a vertical cross-section, the preferred form thereof.

Fig. 3 illustrates in vertical axial cross-section an elbow valve, embodying the features of my invention.

50 Fig. 4 is a vertical axial sectional view of an elbow form of valve, embodying the features of my invention in modified form.

Fig. 5 is a cross-sectional view taken on the plane of the line 6, 6, of Fig. 1 and look-

ing in the direction indicated by the arrows, 55 and

Fig. 6 is a sectional view taken on the plane of the line 7, 7, of Fig. 4, looking in the direction indicated by the arrows.

Referring first to Fig. 1, it will be seen 60 that I provide a valve body 8 which is provided with the inlet and outlet openings 9, 9, threaded internally for the reception of connecting pipes. The valve here shown is a key-valve and the upright portion 10 65 thereof is provided with a square chamber for the reception of the movable valve part or gate 11. This gate, as illustrated in Figs. 1 and 5 is centrally divided and when in its lower position is adapted to fit snugly in the 70 pocket 12. The vertical dimension of the part 10 is sufficient to receive the valve part 11 when it is moved in its open position. The upper part of the part 10 is made circular and is internally screw-threaded as 75 illustrated at 13 for the reception of a cap 14. The valve stem 15 is screw-threaded axially in the cap 14, being packed by means of the auxiliary packing cap 16 holding the packing 17 in place. The valve stem is 80 provided with the hand wheel 18. The lower part of the stem 15 is screw-threaded into the joined parts of the gate 11. The lower screw-thread is of the same pitch 85 as the upper screw-thread but is in the opposite direction and only one face of the thread is oblique, this being the upper face, the lower face being normal to the axis of the stem. The under side of the gate 11 is provided with the cylindrical pocket 19 90 which is provided with the oblique upper wall 20. Within this pocket the stem 15 is provided with a wedging head 21 which engages the wall 20, as clearly shown in 95 Fig. 1.

It will now be seen, since the part 11 is held against rotation by means of its snug engagement in the square chamber, that when the hand wheel 18 is turned in a counterclockwise direction, the stem 15 will 100 rise in the cap 14 and the gate 11 will rise about the stem 15. In this way, the gate 11 will travel upward twice as fast as the stem itself and only a few turns are required to open the valve to full open position.

When the hand wheel 18 is turned in a clockwise direction the stem 15 will move downwardly and the gate 11 will climb 105

downwardly on the stem 15 at a rate of speed equal to that of the stem, making the rate of speed of the gate relative to the casing or body twice that of the stem. 5 When the gate 11 reaches its lowermost position, that is with the wall 20 engaging with the oblique surface of the wedging head 21 on the stem, a spreading or wedging action begins and continues with the 10 continued movement of the hand wheel 18 in a clockwise direction. This spreading action is due to the wedging of the two parts of the gate 11 down upon the wedging head 21 and also due to a separating action 15 of the gate 11 due to the formation of the threads on the lower part of the stem 15. In this way the two halves of the gate member are firmly jammed against the sides of the rectangular chamber and an absolutely 20 closed joint is provided at 22, 22. Reference to Fig. 6 will assist in an understanding of this description.

Referring now to Fig. 2, it will be seen that I provide a structure like that of Fig. 1 with, however, some very important additions. The valve body or casing 23 is provided with the inlet and outlet openings 24 25 which are surrounded by engaging flanges 25, 25, provided for the purpose of making 30 connections to pipe lines. The movable valve portion or gate 26 is generally similar to the valve portion or gate 11 of the structure of Fig. 1. It is of rectangular cross-section and it operates in the corresponding 35 vertical chamber 26', this chamber 26' extending both above and below the horizontal portion of the valve body, as illustrated. The top of the vertical portion of the valve body is provided with a flange 27 to which 40 the flange 28 of a cap 29 may be secured by means of bolts 30, 30. The cap is provided with a yoke 31 upon the top thereof and the stem 32 is screw-threaded in this yoke 31, as 45 illustrated. The top of the stem 32 is squared, as illustrated at 33, for the reception of a hand wheel (not shown). The stem 32 is packed in the cap 29 by means of the packing 34 held in place by means of the bushing 35. The lower portion of the stem 50 32 is provided with two wedging members 36, 36, which are adapted to engage oblique walls, 37, 37, upon the respective halves of the gate member. The stem between these 55 two wedging parts 36 is screw-threaded, as illustrated at 38, this screw-thread being opposite in direction to the screw-threads at the upper part of the stem and being of the same nature as the screw-threads upon the lower portion of the stem in the structure of 60 Fig. 1. The general action is the same as in Fig. 1. When the stem 32 is turned in a counterclockwise direction the valve part 26 rises upon the stem and with the stem, the pocket 39 being provided for the movement 65 of the upper part 36 relative to the parts 26,

It will be seen that the chamber 26' is supplemented by a pocket 40 on each side thereof, this pocket being annular and surrounding the respective passageways. A ring seat 41 is disposed in each pocket and a 70 clamping ring 42 having engagement with the seat ring 41 is disposed inside the ring 41, the two rings having conical engaging surfaces, as clearly illustrated. A bushing 43 screw-threads internally in the clamping 75 ring 42 and, upon its outer end, is provided with a flange 44 which is disposed in a pocket 45 surrounding the passageways. It will now be seen that the bushing 43 may readily be interchanged so as to secure the 80 proper size of internal opening and that it is not necessary to provide internal finish for the valve body except in these removable parts. The valve gate or movable member 26 firmly engages the seat 41 on both sides, 85 as illustrated. In its uppermost position, the part 26 is guided by the guiding pieces 46, 46, so that in initiating the downward movement of the valve member, the stem will not be caused to skew from one side to the other. 90

I now come to a very important phase of my invention. The vertical chamber 26' is supplemented at the bottom by a pocket 47 and a valve seat cover member 48 is disposed in this pocket when the valve is in its 95 lowermost position, this valve seat cover member being integral and extending downwardly from the valve part 26. This valve seat cover member is provided with a bore 49 which is adapted to register with the 100 horizontal passageway of the valve body when the valve gate is in its uppermost position, and it will be noted that when in this position the cover member clearly is seated upon the seat ring 41, all the way around, thus effectively protecting the seat against 105 the action of the fluid passing through the line—such as the injurious action of rushing steam.

It will be seen when I lower the valve part 110 26 by turning the stem 32 in a clockwise direction, the wedging, described relative to Fig. 1, will follow by reason of the engagement of the wedging heads 36, 36, with the oblique walls, 37, 37, and also the wedging 115 action of the threads about the lower part of the stem, due to the peculiar formation of these threads. Thus, when the valve is in closed position, I get an absolutely tight joint and when it is in open position, I effectively protect the valve seat against injurious action.

Referring now to Fig. 3, it will be seen that I embody the features of my invention in approximately the same kind of structure, 125 except that the structure is an elbow valve instead of a straight valve. The valve body is illustrated at 26 and it may be assumed that the passageway 51 is the inlet opening while the passageway 52 is the outlet opening, 130

flanges 53 and 54 being respectively provided to connect these openings with the pipe line. So far as the description of the Fig. 2 applies to Fig. 3, the same reference characters have been used, and it will be unnecessary to repeat this description here. A seat ring is provided only upon one side and when the valve is in raised position, the seat ring is effectively covered just as heretofore described. However, the lower portion of the seat cover is provided with the opening 53' through which the fluid may pass, in addition to the passage of fluid in the part 54'. The stem 32, in this instance, is threaded in the cap 55 which is provided with the auxiliary cap 56 to form a stuffing box 57. Furthermore, in this instance, only one wedging head 36 is provided, but the action is the same in kind.

In Fig. 4, I illustrate still another type of valve embodying the wedging and seat covering principles of my invention. This is an elbow structure, the valve body or casing being shown at 60. The inlet 61 is surrounded by the connecting flange 62 and the outlet opening 63 is surrounded by the connecting flange 64. In this instance, the cap arrangement is substantially that of Fig. 1 and the parts have been similarly lettered. However, in this structure, the chamber 65 is cylindrical and a bushing 66, which is finished while the remainder of the chamber may be unfinished, is slipped into this chamber, the lower portion of the bushing 66 being provided with a valve seat 67.

The valve 68 is composed of three portions, the two side portions 69, 69, and the bottom portion 70. The bottom portion 70 is provided with an oblique surface 71 seated upon the conical seat 67 upon the bushing 66. This bottom portion is also provided with an upper conical surface 72 which the bottom conical surface 73 upon the portions 69, 69, engages. The screw 74 holds the bottom part to the side pieces, but permits of a little play between the two parts. The stem, in this instance, is not provided with a wedging head, but the lowermost screw-thread is of the form of the lowermost screw-thread of Figs. 1 and 2.

Extending downwardly from the valve portion 70 is a member 75 which carries the seat cover or protector 76, this member being provided with guiding lugs 77 as clearly shown in Fig. 6. The gate is shown in its closed position, and it will be obvious, as heretofore explained, that when the hand wheel is turned in its counterclockwise direction, the gate will climb upwardly upon the stem and also move upwardly with the stem. This opens the passageway between the inlet and outlet and when the valve is brought to its uppermost position, the protecting or covering ring 76 will be disposed just inside the valve seat 67. So far as pro-

tectioning the valve seat against rushing steam is concerned, the fact that the protecting ring 76 does not touch the valve seat is immaterial, since nevertheless the proper protection toward which I am aiming is secured. However, I do place the ring 76 in the valve seat so as to prevent any possibility of the collection of slime in a pocket, which might otherwise be formed. When the valve stem is turned in its clockwise direction the gate 75 is brought downwardly and when the under oblique surface 71 of the part 70 engages the valve seat 67 it will arrest its movement, but the parts 69, 69 will continue to come down and will jam the part 70 down upon its valve seat while, at the same time, these parts themselves will be jammed firmly in the bushing 66 by reason of the wedging action between the surfaces 72 and 73, and also by reason of the wedging action of the screw-threads on the lowermost portion of the stem.

I claim as new and desire to secure by Letters Patent:

1. In a valve, a body providing a chamber, an inlet and an outlet therefor, a two-part gate having an oblique surface for reciprocating in said chamber, a stem threaded in said body and threaded in said gate, the latter threads being normal on one face and oblique on the other to secure a wedging action to expand said gate, the two sets of threads on the stem being in opposite directions, and a wedging member carried by said stem for engaging the oblique surface in said gate for spreading the same.

2. In a valve, a body providing a chamber, an inlet and an outlet therefor, an expansible gate for reciprocating in said chamber, a stem for turning in said body, and threaded in said gate, the thread being normal on one face and oblique on the other to secure a wedging action to expand said gate.

3. In a valve, a body providing a chamber, an inlet and an outlet therefor, an expansible gate for reciprocating in said chamber, a stem threaded in said body and threaded in said gate, the latter thread being normal on one face and oblique on the other to secure a wedging action to expand said gate.

4. In a valve, a body providing a chamber, an inlet and an outlet therefor, an expansible gate for reciprocating in said chamber, a stem threaded in said body and threaded in said gate, the latter thread being normal on one face and oblique on the other to secure a wedging action to expand said gate, said threads being in opposite directions.

5. In a valve, a body providing a chamber, an inlet and an outlet therefor, an expansible gate having an oblique surface, for reciprocating in said chamber, a stem threaded in said body and threaded in said gate,

the latter thread being normal on one face and oblique on the other to secure a wedging action to expand said gate, the two sets of threads on the stem, being in opposite directions, and a plurality of wedging members carried by said stem for engaging the oblique surface in said gate for spreading the same.

6. In a valve, a body providing a chamber, an inlet and an outlet therefor, a two-part gate having an oblique surface, for reciprocating in said chamber, a stem threaded in said body and threaded in said gate, the latter thread being normal on one face and oblique on the other to secure a wedging action, the two sets of threads on the stem, being in opposite directions, and a plurality of wedging members carried by said stem for engaging the oblique surface in said gate for spreading the same.

7. In a valve, a body providing a chamber, an inlet and an outlet therefor, an expandable gate for reciprocating in said chamber, a stem for turning in said body, and

threaded in said gate, the thread being normal on one face and oblique on the other to secure a wedging action to expand said gate, and means for covering the valve seat when the valve is in open position.

8. In a valve, a body providing a chamber, an inlet and an outlet therefor, an expandable gate having an oblique surface for reciprocating in said chamber, a stem turning in said body, and threaded in said gate, the threads being normal on one face and oblique on the other to secure a wedging action to expand said gate, and a wedging member carried by said stem for engaging the oblique surface in said gate for spreading the same.

In witness whereof, I hereunto subscribe my name this 22nd day of March A. D. 1915.

JOHN M. PALMER.
